RAILWAY SIGNALING SYSTEM

Frank H. Nicholson, Penn Township, Allegheny County, Pa., assignor to The Union Switch & Signal Company, Swissvale, Pa., a corporation of Pennsylvania

Application May 18, 1940, Serial No. 335,992

13 Claims. (Cl. 246—130)

My invention relates to railway traffic controlling apparatus of the type employing coded current in the track circuits thereof, and particularly to means for discontinuing operation of highway crossing signals or for controlling other apparatus conditioned upon occupancy of a track section.

One advantage of the use of coded or periodically interrupted current in track circuits is the improved shunting sensitivity which results from the use of energy of this type. If steady uncoded energy is supplied to a track section to discontinue operation of a highway crossing, or to determine occupancy of the track section for any other purpose, the advantage of improved shunting sensitivity resulting from the use of coded energy is lost as long as steady energy is supplied to the track section.

It is an object of this invention to provide an improved railway signaling system employing coded or periodically interrupted energy in the track circuits to control the signals governing movement of trains in the track stretch, and incorporating means for at times employing coded energy in a track section to detect occupancy of the section without affecting the traffic governing signals.

A further object of the invention is to provide an improved signaling system of the type described, the equipment being arranged so that when coded energy is supplied to a track circuit for detection purposes the track relay of the track circuit is disconnected to thereby prevent response of the track relay to the energy supplied for detection purposes.

Another object of the invention is to provide an improved signaling system of the type described, the equipment being arranged so that when a train enters a track section operation of a highway crossing signal is initiated, and having means for supplying coded energy to the track circuit at the entrance end of the section together with code responsive means at the exit end of the section for discontinuing operation of the crossing signal when the train vacates the section.

A further object of the invention is to provide in a railway signaling system of the type employing coded or periodically interrupted energy in the track circuits thereof, means for controlling a highway crossing signal, this means being arranged so that it does not require a code following track relay to respond to uncoded energy.

Another object of the invention is to provide

a railway signaling system incorporating means for controlling a highway crossing signal, the system being arranged so that failure of line wires employed therein will affect only the crossing signals and will not interfere with the intended operation of the signals governing movement of trains in the track stretch.

Other objects of the invention and features of novelty will be apparent from the following description taken in connection with the accompanying drawings.

I shall describe one form of railway signaling system embodying my invention, together with a modification which I may employ, and shall then point out the novel features thereof in claims.

In the drawings:

Fig. 1 is a diagram of a stretch of railroad track equipped with signaling apparatus embodying my invention, and

Fig. 2 is a diagram showing a modification which I may employ.

Referring to the drawings, there is shown therein a stretch of railroad track having track rails 1 and 2 over which traffic normally moves in the direction indicated by the arrow, that is from left to right.

The rails of the track stretch are divided by insulated joints 3 into track sections for signaling purposes. One of the track sections includes an intersection with a highway and the rails of this section have additional insulated joints 3 therein to divide the section into an approach section B11T and a clearing section A11T to facilitate control of the crossing signals XS which protect the intersection. Portions of two other track sections are shown and are identified as sections 10T and 12T.

Each of the principal track sections has located at the entrance end thereof a wayside signal for indicating to approaching trains the nature of the traffic conditions in advance. As shown these signals are of the familiar color light type, each having a green or clear lamp G, a yellow or caution lamp Y, and a red or stop lamp R. The wayside signals are designated 11S and 12S in the drawings.

It is to be understood that the invention is not limited to a system employing this type of signals, however, and that any suitable type of wayside signals may be employed. The invention is also applicable to track stretches which do not have wayside signals, but employ cab signals only.

The rails of each of the track sections form

a part of a track circuit to which coded alternating current signal control energy is normally continuously supplied at the exit or leaving end of the section from a current supply device in the form of a track transformer designated TT with an appropriate prefix.

Each of the track circuits includes, in addition, an electroresponsive device in the form of a code following track relay having a winding receiving energy from the rails of the section at a point adjacent the entrance end of the section.

The circuits for supplying energy from the track transformer secondary windings to the rails of the track sections include the usual current limiting reactors 6.

The energy supplied to the track circuits is derived from any suitable source, and may be distributed throughout the track stretch by a transmission line, not shown. In the drawings the reference characters BX and CX designate the terminals of such power supply source, and it will be assumed that the energy supplied from this source is alternating current of a frequency of 100 cycles per second.

The signaling system shown in the drawings is of the three-indication variety and makes use of track circuit energy coded at two different frequencies. This coded energy is provided by code transmitters CT which interrupt the circuits of the associated track transformers a definite number of times a minute according to traffic or other conditions in advance. In the illustrative form shown each code transmitter CT is provided with two circuit making and breaking contacts 15 and 180 which are continuously actuated by a motor or other suitable mechanism at two different speeds. For purposes of illustration it will be assumed that these speeds are such as to provide 75 and 180 energy pulses per minute which are separated by periods of equal duration in which no energy is supplied.

The track relays TR may be of any suitable type, and, as shown, are of the direct current type, each having a winding connected to the track rails of the associated track section through a suitable resonant rectifier unit RU shown diagrammatically in the drawings.

The resonant rectifier units RU each comprise a transformer, a capacitor and a reactor so arranged and proportioned as to freely pass the 100 cycle signal control energy, but so as not to pass energy of a different frequency, while a rectifier is incorporated in each unit to convert into direct current the alternating current which is supplied through the unit.

Each of the track relays has associated therewith a suitable source of direct current, such as a primary or a storage battery, not shown, the terminals of which are designated B and C in the drawings.

The track relay TR at the entrance end of each principal track section has associated therewith decoding means comprising a decoding transformer DT, and auxiliary relays H and J. The decoding means is not a part of this invention, and any suitable apparatus well known in the art may be employed for this purpose.

The track relay A11TR for the clearing section A11T has associated therewith a front contact repeater relay A11FSA and a back contact repeater relay A11BSA.

The approach section B11T is provided with a second or reverse track circuit in addition to the usual or normal track circuit. The second track circuit includes a supply device in the form of a

secondary winding on the transformer 10TT. As hereinafter explained this secondary winding is at times connected with the rails of section B11T adjacent the entrance end of the section. The

5 second track circuit also includes an electroresponsive device in the form of a code following track relay N which has a winding which at times is connected through a resonant rectifier unit NRU to the rails of section B11T adjacent the exit end of the section.

10 An interlocking relay XR is provided to control the crossing signals XS, while a slow releasing auxiliary relay M is provided to control the supply of energy to one winding of the interlocking relay, and to also control a circuit for supplying energy to the crossing signals XS. The circuit of the winding of the relay M is controlled by the track relay N so that the relay M is at times energized by current supplied over line wires 15 and 16, and at other times is energized by current supplied from the local source of direct current.

15 The track relay B11TR has associated therewith an auxiliary relay P which is energized at times by current supplied over the line wires 15 and 16.

20 The equipment is shown in the drawings in the condition which it assumes when the track stretch is vacant. At this time energy of 180 code frequency is supplied to the track transformer 12TT by the equipment associated with the section in advance of section 12T. This energy feeds to the track relay 12TR and produces code following operation of the contacts of this track relay.

25 On movement of the track relay contact 20 to its picked-up position a circuit is established to supply energy from the local source of direct current to the upper half of the primary winding of the decoding transformer 12DT, while on movement of the track relay contact 20 to its released position energy is supplied to the lower half of the transformer primary winding. As a result of alternate energization of the two halves 30 of the transformer primary winding, impulses of energy are induced in the secondary windings 23 and 24, while the track relay contact 21 rectifies the current supplied from the secondary winding 23 to the winding of the relay 12H. As the winding of the relay 12H is energized the contacts of this relay are picked up.

35 As the track relay 12TR is responding to energy of the 180 code frequency the frequency of the current induced in winding 24 is such that sufficient energy is supplied through the resonant unit 12RUA to the winding of relay 12J to pick up the relay contact.

40 As contact 25 of relay 12H and contact 21 of relay 12J are picked up the circuit of the green or clear lamp G of signal 12S is established, and this lamp is lighted to indicate that there are at least two unoccupied sections in advance of the signal.

45 As contact 28 of relay 12H is picked up the circuit for supplying energy of the 180 code frequency to the track transformer A11TT is established, and energy supplied through this transformer feeds to the track relay A11TR and produces code following operation of the relay.

50 On movement of the track relay contact 30 to its picked-up position energy is supplied to relay A11FSA, while on movement of track relay contact 30 to its released position energy is supplied to relay A11BSA over a circuit which includes front contact 31 of relay A11FSA. A

snubbing resistor 32 is connected across the terminals of the winding of the relay A11FSA to render the relay contacts slow in releasing, while a snubbing resistor 33 is connected across the terminals of the winding of the relay A11BSA as long as the contact 31 of relay A11FSA is picked up. The relays A11FSA and A11BSA and the snubbing resistors are selected so that the relay contacts will remain picked up during the intervals between the supply of impulses of energy to the relay windings when the track relay A11TR is responding to coded energy.

At this time, therefore, contact 34 of relay A11BSA is picked up and establishes a circuit through which energy is supplied to the primary winding 36 of the track transformer B11TT when track relay contact 35 is in its picked-up position. This circuit is interrupted on release of the track relay contact 35 so that as long as the track relay A11TR is responding to coded energy, the energy supplied to the track transformer B11TT is coded at the same frequency as the energy which is supplied to the relay A11TR.

The circuit of the secondary winding 38 of the track transformer B11TT includes in series therewith the primary winding 40 of the transformer incorporated in the resonant rectifier unit NRU associated with the relay N. The circuit of the secondary winding 41 of this transformer is controlled by contact 42 of relay A11BSA so that the circuit is complete when and only when contact 42 is released. At this time as contact 42 is picked up this circuit is interrupted and energy is not supplied through this resonant unit to the winding of the relay N.

The transformer of which the primary winding 40 forms a part is selected so that the impedance of the winding 40 at a time when the circuit of the secondary winding 41 is interrupted is such that the supply of current from the track transformer B11TT to the rails of section B11T is not unduly diminished, while this factor is taken into consideration in selecting the reactor 6. Accordingly sufficient current is supplied from the transformer B11TT to the rails of section B11T to insure proper operation of the track relay B11TR.

At this time, as contact 43 of relay A11BSA and contact 44 of relay A11FSA are picked up, energy is supplied to the winding 46 of the interlocking relay XR and the armature controlled by this winding is picked up with the result that contacts 47 and 48 establish connection from the line wires 15 and 16 to the back contacts of relay N. In addition, contact 49 of the interlocking relay XR is picked up and establishes the circuit which is also controlled by a contact of relay M for supplying energy to the winding 54 of the interlocking relay XR.

The relay N is not energized at this time as contact 42 of relay A11BSA interrupts the circuit of the resonant unit NRU associated with the relay N. The contacts 50 and 51 of relay N, therefore, are released and engage their back contacts and establish the circuit to supply energy from the line wires 15 and 16 to auxiliary relay M. At this time energy is supplied to the line wires 15 and 16 by means associated with relay B11TR as hereinafter explained in detail.

As the relay M is energized its contacts 52 and 53 are picked up, and contact 53 establishes the circuit through which energy is supplied to the winding 54 of the interlocking relay XR so that the armature controlled by this winding is picked up.

As both windings of the interlocking relay XR are energized both armatures of the relay are picked up and the crossing signals XS are maintained inactive.

5 As contact 52 of relay M is picked up one circuit for supplying energy to the crossing signals XS is interrupted, and as contact 49 of the interlocking relay XR is picked up the other circuit for supplying energy to the crossing signals XS is interrupted, and, accordingly, the crossing signals are inactive at this time.

As pointed out above energy of the 180 code frequency is supplied to the track relay A11TR, and this relay repeats the supply of energy of this code frequency to the rails of section B11T. Energy supplied to the rails of section B11T is supplied through the resonant unit B11RU to the track relay B11TR and produces code following operation of this relay.

10 15 20 25 30 The circuit for connecting the resonant unit B11RU with the rails of section B11T includes a back contact of contact 55 of auxiliary relay P. The relay P is deenergized at this time, so that the circuit for supplying energy from the rails of section B11T to the track relay B11TR is complete.

35 40 45 50 55 As the track relay B11TR is responding to coded energy of the 180 code frequency, current is supplied through the decoding transformer B11DT to the windings of the relays B11H and B11J and these relays are picked up. As the contact 25 of relay B11H and contact 27 of relay B11J are picked up the circuit of the green or clear lamp G of signal 11S is established, while as contact 28 of relay B11H is picked up the circuit for supplying energy of the 180 code frequency to the primary winding of the track transformer 10TT is established. Accordingly impulses of current are induced in the secondary winding 57 of this transformer and energy is supplied from this winding to the rails of section 10T.

The track transformer 10TT is provided with another secondary winding 58 from which energy is at times supplied to the rails of section B11T. The circuit for supplying energy from the winding 58 is complete only when contact 55 of auxiliary relay P is picked up, and as this contact is released at this time energy is not supplied from winding 58 to the rails of section B11T.

55 60 65 70 75 As the contacts of relay B11H are picked up contacts 60 and 61 establish the circuit to supply energy from the local source of direct current to the line wires 15 and 16 over which energy is supplied to the winding of the auxiliary relay M at this time.

Operation of equipment on passage of a train through the track stretch in the normal direction of traffic

When a train moving in the normal direction of traffic enters the approach section B11T the track relay B11TR is shunted and energy is no longer supplied through the decoding transformer B11DT to relays B11H and B11J and these relays become released.

70 75 80 85 90 As a result of the release of relay B11H the circuit of the green lamp G of the signal 11S is interrupted, and the circuit of the red or stop lamp R is established. On release of the contact 28 of relay B11H the circuit for supplying energy of the 180 code frequency is interrupted, while the circuit for supplying energy of the 75 code frequency to the transformer 10TT is established,

and energy of this code frequency is supplied from the transformer to the rails of section 10T.

On release of relay B11H contacts 60 and 61 interrupt the supply of energy to the line wires 15 and 16 and establish connection from the line wires 15 and 16 to auxiliary relay P.

On interruption of the supply of energy to the line wires 15 and 16 the supply of energy to the auxiliary relay M is interrupted, and relay M releases and contact 53 interrupts the circuit of the winding 54 of the interlocking relay XR. Accordingly, the armature controlled by this winding becomes released and contact 62 engages its back contact. As contact 52 of auxiliary relay M is in its released position a circuit is established to supply energy to the crossing signals XS, and these signals operate to warn users of the highway of the approach of a train.

When the train advances far enough in the track stretch to enter the clearing section A11T, the track relay A11TR is shunted and energy is no longer supplied to relay A11FSA with the result that this relay releases and interrupts the circuit of relay A11BSA so that this relay releases.

On release of contact 34 of relay A11BSA the circuit for supplying energy to the primary winding 36 of the track transformer B11TT is interrupted, while at this time the track relay contact 35 is in its released position and engages its back contact to thereby establish a circuit short circuiting the primary winding 36 of the track transformer B11TT. As the primary winding of the transformer B11TT is short circuited the impedance of the secondary winding 38 is reduced to a minimum.

On release of contact 44 of relay A11FSA the circuit of the winding 46 of the interlocking relay XR is interrupted, and the armature controlled by this winding moves towards its released position so that contacts 47, 48 and 49 interrupt the circuits controlled thereby. However, because of the internal construction of the interlocking relay XR the armature controlled by winding 48 is prevented from moving all of the way to its released position since the other armature of the relay is already in its released position.

On release of the contacts 43 and 63 of relay A11BSA energy is supplied to the line wires 15 and 16 from the source of direct current associated with relay A11TR. The circuit for supplying energy to the line wires is complete at this time as contacts 64 and 65, which are controlled by winding 54 of the interlocking relay XR, are released.

When the contacts of the relay A11FSA and of the interlocking relay XR establish connection from the local source of direct current to the line wires 15 and 16, energy is supplied over the line wires 15 and 16 to the auxiliary relay P through the contact 60 and 61 of relay B11H which are released at this time.

On the supply of energy to relay P contact 55 of this relay picks up and interrupts the circuit for connecting the track relay B11TR with the rails of section B11T, and establishes the circuit for supplying energy from the secondary winding 58 of the track transformer 10TT to the rails of section B11T.

As pointed out above at this time, as the track relay B11TR is not responding to coded energy, the relay B11H is not energized and its contact 28 is released so that energy of the 75 code frequency is supplied to the primary winding of the track transformer 10TT, and on establishment 75

of the circuit of the winding 58 of the transformer 10TT energy of the 75 code frequency is supplied to the rails of section B11T.

From the foregoing it will be seen that when a train moving in the normal direction of traffic enters the clearing section A11T, the contacts of the relay A11BSA release and interrupt the supply of energy to the rails of section B11T through the transformer B11TT, that is, the supply device of the first track circuit of section B11TT, while contact 42 of relay A11BSA establishes the circuit for supplying energy from the rails of section B11T to the winding of the relay N, that is, the electroresponsive device of the second track circuit of section B11T.

In addition, at this time energy is supplied over the line wires 15 and 16 to the winding of the relay P to pick up this relay. When contact 55 of relay P is picked up it interrupts the circuit for supplying energy from the rails of section B11T to the winding of the track relay B11TR, that is, the electroresponsive device of the first track circuit of section B11T, and establishes the circuit for supplying energy to the rails of section B11T from the secondary winding 58 of transformer 10TT, that is, the supply device of the second track circuit of section B11T.

Accordingly, it will be seen that when the train enters the clearing section T11T, the supply device and the electroresponsive device of the first track circuit of the approach section B11T are both rendered inactive, while the devices of the second track circuit of section B11T are both rendered active and the second track circuit serves to detect when the train vacates the approach section.

As long as any portion of the train remains in the approach section B11T the energy supplied at the entrance end of the section cannot feed to the relay N at the exit end of the section. However, as soon as the rear of the train clears the approach section B11T energy feeds from the entrance end of the section to the primary winding 40 of the transformer which is included in the resonant rectifier unit NRU associated with the relay N. The circuit of the primary winding 40 includes in series therewith the secondary winding 38 of the track transformer B11TT, but, as pointed out above, the impedance of this winding is at a minimum at this time since the primary winding 36 of the transformer is short circuited. Accordingly, energy may flow freely in the circuit of the transformer primary winding 40.

At this time contact 42 of relay A11BSA is released and establishes the circuit of the secondary winding 41 of the transformer of the resonant unit NRU. The resonant unit NRU includes a capacitor and an inductance which are arranged and proportioned so as to freely pass the alternating current energy of 100 cycle frequency which is employed in the signal system and so as not to pass energy of different frequencies. This unit also includes a rectifier which converts into direct current the alternating current which is supplied through the unit to the winding of the auxiliary relay N.

It will be seen, therefore, that when the rear of the train clears the approach section B11T coded energy feeds through the resonant rectifier unit NRU to the winding of the relay N, and the contacts of this relay are picked up and released in response to the supply of impulses of coded energy to the relay winding.

On movements of the contacts 50 and 51 of

relay N to their picked-up position energy is supplied to the relay M from the local source of energy, while the supply of energy to this relay is interrupted during the released periods of the contacts of the relay N. The relay M is of a type the contacts of which are slow in releasing with the result that the relay contacts pick up and remain picked up during the intervals between the supply of impulses of energy to the relay.

On picking up of the contact 52 of relay M the circuit for supplying energy to the crossing signals XS is interrupted and operation of the crossing signals is discontinued.

On picking up of the contact 53 of the relay M the circuit for supplying energy to the winding 54 of the interlocking relay XR is not established since this circuit is interrupted by contact 49 of the relay XR. Accordingly, the armature controlled by the winding 54 of the relay XR remains in its released position and contacts 64 and 65 maintain the circuit for supplying energy to the line wires 15 and 16 so that relay P is energized and its contact 55 is picked up to maintain the circuit for supplying coded energy to the rails of section B11T.

When the train enters section 12T the track relay for this section is shunted and the signal 12S is conditioned to display its red or stop indication, while the energy supplied to the rails of section A11T is changed from 180 to 75 code frequency.

When the train advances far enough in the track stretch to vacate section A11T the energy of 75 code frequency feeds to the track relay B11TR, and produces code following operation of the relay. As a result energy is supplied to the relays A11FSA and A11BSA and these relays pick up.

On picking up of the contacts 43 and 63 of relay A11BSA the supply of energy to the line wires 15 and 16 is cut off, while as a result of picking up of contact 44 of relay A11FSA and of contact 43 of relay A11BSA the circuit is established to supply energy to the winding 46 of the interlocking relay XR so that contacts 47, 48 and 49 become picked up.

On picking up of contact 42 of relay A11BSA the circuit of the resonant rectifier unit NRU is interrupted and energy is no longer supplied through this unit to the winding of the relay N and the contacts of this relay become released and no longer establish the circuit for supplying energy to the winding of the relay M. However, because of the slow releasing characteristic of the relay M the contacts of this relay remain picked up for a time interval and contact 52 continues to interrupt the circuit for supplying energy to the crossing signals XS.

As a result of interruption of the supply of energy to the line wires 15 and 16 on picking up of contacts 43 and 63 of relay A11BSA, the supply of energy to the auxiliary relay P is cut off, and contact 55 of this relay becomes released to interrupt the circuit for supplying coded energy from winding 58 of transformer 10TT to the rails of section B11T, and to establish the circuit for supplying energy from the rails of section B11T to the winding of the track relay B11TR.

When contact 34 of relay A11BSA becomes picked up the circuit is established for supplying impulses of energy to the rails of section B11T during the picked-up periods of contact 35 of track relay A11TR.

It will be seen, therefore, that when the train

vacates the clearing section and the contacts of relay A11BSA become picked up, the devices of the second track circuit of section B11T are rendered inactive, while the devices of the first track circuit of section B11T are rendered active.

The energy which is supplied from transformer B11TT to the rails of section B11T feeds to the track relay B11TR, and the contacts of this relay respond to coded energy so that energy is supplied through the decoding transformer B11DT to pick up relay B11H. As the track relay B11TR is responding to energy of 75 code frequency insufficient energy is supplied through the resonant unit B11RUA to the relay B11J to pick up the contact of this relay.

On picking up of contact 25 of relay B11H the circuit of the red or stop lamp R of signal 11S is interrupted, while the circuit of the yellow or caution lamp Y is established. On picking up of contact 28 of relay B11H the energy supplied to the rails of section 10T is changed from 75 to 180 code frequency.

When contacts 60 and 61 of relay B11H are picked up the relay P is disconnected from the line wires 15 and 16, while energy is supplied to the line wires. At this time contacts 47 and 48 of the interlocking relay XR are picked up, and as contacts 50 and 51 of the auxiliary relay N are released, connection is established from the line wires 15 and 16 to the relay M, and energy is supplied over the line wires to energize the relay.

When the contacts of relay A11BSA become picked up the circuit for supplying energy to the winding 46 of the interlocking relay XR was established and the contacts 47, 48 and 49 became picked up. Contacts 47 and 48 when picked up establish connection from the line wires 15 and 16 to the relay M, while contact 49 when picked up completes the circuit for supplying energy to the winding 54 of the relay XR. This circuit is complete at this time as contact 53 of relay M is picked up.

On the supply of energy to the winding 54 of the interlocking relay XR the armature controlled by this winding becomes picked up and the relay is restored to its normal condition.

It will be seen that the supply of energy to the winding of the auxiliary relay M is interrupted on picking up of the contact 42 of the relay A11BSA and resultant release of the contacts of the relay N, while the supply of energy to the winding of the relay M is resumed on picking up of the contacts of the relay B11H.

The contacts of the relay B11H become picked up shortly after code following operation of the track relay B11TR is initiated, while code following operation of the relay B11TR is started as soon as the contacts of the relay A11BSA become picked up. Accordingly there is only a short interval between the time at which the supply of energy to the relay M is interrupted by release of the contacts of the relay N, and the time at which the contacts of the relay B11H become picked up to establish a circuit to supply energy to the relay M. The relay M is of a type the contacts of which are slow in releasing, and the relay is selected so that its contacts are slow enough in releasing to remain picked up throughout the interval during which energy is not supplied to the relay winding when code following operation of the track relay A11TR is initiated.

As the contacts of the relay M are maintained picked up during the change in the condition of the equipment which occurs when the clearing

section A11T is vacated, contact 52 maintains the circuit of the crossing signals XS open so that these signals are maintained inoperative at this time.

From the foregoing it will be seen that when a train moving in the normal direction of traffic enters the clearing section A11T coded energy is supplied to the rails of the approach section B11T adjacent the entrance end of the section, and that there is at the exit end of the approach section code detecting means in the form of a code following relay N and an auxiliary relay M. When the approach section B11T is vacated coded energy feeds to the code detecting means at the exit end of the approach section and the relay M thereupon operates to discontinue operation of the highway crossing signals.

If while the clearing section A11T is still occupied a second or following train should enter the approach section B11T, the track rails of the section will be shunted and coded energy supplied at the entrance end of the section will not reach the code following relay N at the exit end of the section. The contacts of the relay N, therefore, will remain released and energy will not be supplied to the relay M and the contacts of relay M will become released, and will effect operation of the crossing signals XS to warn users of the highway of the approach of the train.

Since coded energy is employed in the approach section to discontinue operation of the crossing signals when a train vacates the section, the shunting sensitivity of the track circuit of this section at this time is the same as when the track stretch is vacant. Accordingly, there is no danger that when a train enters the approach section at a time when energy is supplied to the section for the purpose of preventing operation of crossing signals that the train will fail to shunt the track circuit and thus fail to effect operation of the crossing signals.

It will be seen also that when coded energy is supplied to the rails of the approach section for the purpose of discontinuing operation of the crossing signals, the track relay at the entrance end of the approach section is disconnected from the track rails of the section so that there is no possibility that this relay will respond to the coded energy which is supplied to the rails of the section at this time.

The coded energy which is supplied to the rails of the approach section B11T for detection purposes is supplied at the entrance end of the section, but this energy cannot effect operation of the cab signal equipment on locomotives traversing the track stretch. Locomotives provided with this equipment have receivers mounted ahead of the leading pair of wheels and receiving energy inductively from the track rails. When a locomotive with this equipment enters the approach section at a time when coded energy is supplied to the rails of the section for detection purposes, the wheels and axles of the locomotive shunt the rails of the section at points between the receivers and the source from which energy is supplied to the rails of the section. Accordingly, energy does not reach the portions of the track rails over which the receivers are located and the receivers will not supply energy to the cab signal apparatus. This apparatus, therefore, will be conditioned to display its most restrictive indication.

The system provided by this invention is arranged so that if the line wires 15 and 16 are defective for any reason, only the highway crossing

signals XS will be affected, while the signals governing movement of trains in the track stretch will continue to function in the normal manner.

5 If, for example, the line wires 15 and 16 become defective at a time when the track stretch is vacant, energy will not be supplied over the line wires to the auxiliary relay M, and the contacts of this relay will be released to thereby interrupt the circuit of the winding 54 of the interlocking relay XR. Accordingly, the armature controlled by this winding of the interlocking relay XR will be released, and, as contact 52 of relay M and contact 62 of the interlocking relay are released, energy is supplied to the crossing signals XS, and these signals are caused to operate even though no train is present in the vicinity. This, however, is a safe condition.

At this time the equipment associated with track relay A11TR operates in the usual manner and energy of the 180 code frequency is supplied through the track transformer B11TT to the rails of section B11T, while the track relay B11TR responds to this coded energy and conditions the signal 11S to display its clear indication.

It will be seen, therefore, that failure of the line wires at a time when the track stretch is vacant results in operation of the crossing signals XS, but it does not interfere with the signals governing movement of trains in the track stretch.

If, while the line wires 15 and 16 are defective, a train moving in the normal direction of traffic enters section B11T, the track relay B11TR will be shunted and the signal 11S will display its stop indication, while energy of the 75 code frequency will be supplied to the rails of section 10T. At this time the contacts of relay B11H will be released to interrupt the supply of energy to the line wires 15 and 16, and to establish connection from the line wires 15 and 16 to the winding of the relay P. As the line wires are assumed to be defective, cutting off of the supply 45 of energy to these wires is without result since the contacts of relay M are already released.

When the train advances into section A11T the track relay A11TR is shunted and the relays A11FSA and A11BSA become released. On release of the contact 34 of relay A11BSA the supply of energy to the track transformer B11TT is cut off, while release of contact 42 establishes the circuit of the resonant unit NRU. On release of contacts 43 and 63 of relay A11BSA, the circuit for supplying energy to the line wires 15 and 16 is established, but as these wires are assumed to be defective, energy is not supplied over the line wires to the relay P. Accordingly, the contact 55 of relay P remains released and does not establish the circuit for supplying energy from the winding 58 of transformer 10TT to the rails of section B11T, while contact 55 maintains the circuit for supplying energy to the winding of the track relay B11TR.

65 At this time, therefore, the track relays B11TR and N are both connected to the rails of section B11T, but the transformers B11TT and 10TT are both ineffective to supply energy to the rails of section B11T, and the contacts of the track relays remain released even after the train vacates section B11T.

As the track relay B11TR is deenergized the signal 11S continues to display its stop indication, and as the relay N is deenergized, energy is not supplied to the winding of relay M and the

contacts of this relay remain released and maintain the circuit for supplying energy to the crossing signals XS. Accordingly, operation of the crossing signals is not discontinued when the train clears section B!!T.

When the train advances far enough to clear section A!!T, energy of the 75 code frequency feeds to the relay A!!TR, and this relay operates to supply energy to the relays A!!FSA and A!!BSA. On picking up of relay A!!BSA the circuit of the resonant unit NRU is interrupted, while the circuit for supplying energy through the transformer B!!TT to the rails of section B!!T is established. Accordingly, energy feeds to the track relay B!!TR and this relay conditions the signal !!S to display its caution indication.

From the foregoing it will be seen that failure of the line wires does not interfere with operation of the signals governing movement of trains in the track stretch, but that the crossing signals are caused to operate continuously instead of only on the approach of a train. This, however, is a safe condition.

The system shown in Fig. 1 is arranged to employ coded current in the second track circuit of the approach section B!!T. This is the preferred arrangement, but it is possible to employ steady energy in this track circuit, and Fig. 2 is a diagram showing this modification.

Construction and operation of modification shown in Fig. 2

The modification shown in Fig. 2 is the same as that shown in Fig. 1, except as hereinafter specifically pointed out, and the same reference characters are employed to identify the apparatus in Fig. 2 as are employed for the corresponding elements of the system shown in Fig. 1.

The single element direct current code following track relay N employed in the system shown in Fig. 1 is not employed in the system shown in Fig. 2. Instead a two element alternating current track relay NA is employed. This relay has two windings, one of which is constantly energized from the source of alternating current signal control energy. The other winding 39 of the relay NA is connected in series with the secondary winding 38 of the track transformer B!!TT, and is thereby connected across the rails of the approach section B!!T.

The contacts 50 and 51 of relay NA control the circuit of the winding of the relay M in substantially the same manner as in the system shown in Fig. 1.

The track transformer B!!TT in the modification shown in Fig. 2, does not have a secondary winding for supplying energy to the rails of section B!!T. Instead a separate transformer TTA is employed for this purpose. The primary winding 70 of this transformer is constantly energized from the source of alternating current signal control energy. The secondary winding 72 of this transformer is at times connected across the rails of section B!!T over a circuit which includes front contact 55 of relay P, while contact 55 of relay P also controls the circuit of the track relay B!!TR.

The operation of the modification shown in Fig. 2 is substantially the same as that shown in Fig. 1. When the track stretch is vacant the relay A!!TR responds to coded energy with the result that the relays A!!FSA and A!!BSA are energized. Accordingly, during the picked-up

periods of the track relay contact 35 energy is supplied to the primary winding 36 of the track transformer B!!TT so that energy is supplied from the transformer secondary winding 38 to the rails of section B!!T over the circuit which includes in series therewith the winding 39 of the relay NA.

The relay NA is of a type the contacts of which will become picked up only when the instantaneous polarity of the impulses of alternating current energy in the two windings bear a particular relationship to each other. The circuit connections of the two windings of the relay NA and of the track transformer B!!TT are arranged so that when energy is supplied from the transformer to the rails of section B!!T, the instantaneous polarity of the current in the two windings of the relay NA is such that the relay contacts do not become picked up. Accordingly, contacts 50 and 51 remain released and maintain the circuit over which energy is supplied to the winding of relay M from the line wires 15 and 16.

At this time both windings of the interlocking relay XR are energized, as explained in connection with the system shown in Fig. 1, and the crossing signals XS are maintained inactive. In addition, the relay P is deenergized so that the winding of the track relay B!!TR is connected across the rails of section B!!T, while the circuit of the secondary winding 72 of the transformer TTA is interrupted so that energy is not supplied by this transformer to the rails of section B!!T. The track relay B!!TR responds to coded energy and causes the signal !!S to display its clear indication.

When a train traveling in the normal direction of traffic enters the approach section B!!T the track relay B!!TR is shunted and the signal !!S is caused to display its stop indication, while the relay B!!H releases and interrupts the supply of energy to the line wires 15 and 16 and establish connection from the line wires 15 and 16 to the winding of the relay P.

On interruption of the supply of energy to the line wires 15 and 16 the contacts of relay M become released, thereby interrupting the circuit of the winding 54 of the interlocking relay XR, and initiating operation of the crossing signals XS to warn users of the highway of the approach of a train.

When the train advances into the clearing section A!!T the track relay A!!TR is shunted, and the contacts 43 and 63 of relay A!!BSA become released to establish the circuit for supplying energy to the line wires 15 and 16 and thus to the relay P. Accordingly, the contact 55 of this relay becomes picked up to interrupt the circuit of the track relay B!!TR, and to establish the circuit for connecting the secondary winding 72 of transformer TTA across the rails of section B!!T. Steady uncoded energy is thereupon supplied from the transformer TTA to the rails of section B!!T, and when the train vacates the clearing section B!!T this energy feeds to the winding 39 of the relay NA.

The various parts of the equipment are arranged so that when energy is supplied from the transformer TTA to the winding 39 of the relay NA, the instantaneous polarity of the impulses of energy supplied to the two windings of the relay is such that the relay picks up and establishes a circuit to supply energy to the winding of the relay M. The contacts of relay M thereupon become picked up, and contact 52 interrupts the supply of energy to the crossing signals

XS so that operation of these signals is discontinued.

When the train advances far enough in the track stretch to vacate section A11T the track relay A11TR responds to coded energy and supplies current to relays A11FSA and A11BSA.

When the contacts of relay A11BSA become picked up the circuit for supplying energy to the line wires 15 and 16 is interrupted. In addition, energy is supplied to the winding 46 of the interlocking relay XR, and the circuit for supplying energy to the primary winding 36 of the track transformer B11TT is established.

On interruption of the supply of energy to the line wires 15 and 16 the relay P is deenergized, 15 and its contact 55 becomes released to interrupt the circuit for supplying steady energy from the transformer TTA to the rails of section B11T, and to establish the circuit for supplying energy from the rails of section B11T to the winding of the relay B11TR.

On interruption of the supply of energy from the transformer TTA to the rails of section B11T the contacts of relay NA become released and interrupt the supply of energy to relay M. However, because of the slow releasing characteristic of the relay M the contacts of this relay remain picked up until energy is supplied to the relay winding over the line wires. Accordingly, contact 52 interrupts the circuit for supplying energy 30 to the crossing signals XS, and these signals do not operate during this change in the condition of the equipment.

As a result of the supply of energy to the track relay B11TR energy is supplied through the decoding transformer B11DT to the relay B11H, 35 and this relay picks up to establish the circuit for supplying energy over the line wires 15 and 16 to the relay M, and the contacts of this relay are thereafter maintained picked up.

In the event the line wires 15 and 16 are defective for any reason, the modification shown in Fig. 2 operates in such a manner that only the highway crossing signals are affected, while the signals governing movement of trains in the track stretch continue to function in the intended manner.

While the invention has been illustrated and described in connection with the control of highway crossing signals, the system is not limited to use in this manner, but may be employed wherever it is desired to detect occupancy of a track circuit.

Although I have herein shown and described only two forms of railway signaling system embodying my invention, it is understood that various changes and modifications may be made therein within the scope of the appended claims without departing from the spirit and scope of my invention.

Having thus described my invention, what I claim is:

1. In combination, a section of railway track, a first supply means for at times supplying coded energy to the rails of said section adjacent the exit end of the section, a second supply means for at times supplying coded energy to the rails of said section adjacent the entrance end of the section, a first code responsive device having a winding to which energy may be supplied from the rails of said section adjacent the entrance end of the section, a second code responsive device having a winding to which energy may be supplied from the rails of said section adjacent the exit end of the section, a relay responsive to traffic

traffic conditions in the adjacent section in advance of said section and effective when such adjacent section in advance is vacant to condition the first supply means to supply energy to the rails of said section, to render the second supply means ineffective to supply energy to the rails of said section, to render the first code responsive device responsive to coded energy supplied to the rails of said section and to render the second code responsive device non-responsive to coded energy supplied to the rails of said section, said relay responsive to traffic conditions in said adjacent section in advance of said section being effective when such adjacent section in advance is occupied to condition the second supply means to supply energy to the rails of said section, to render the first supply means ineffective to supply energy to the rails of said section, to render the first code responsive device non-responsive to coded energy supplied to the rails of said section, and to render the second code responsive device responsive to coded energy supplied to the rails of said section, and indication means controlled jointly by said first and second code responsive devices.

2. In combination, a section of railway track, a first supply means for at times supplying coded energy to the rails of said section adjacent the exit end of the section, a second supply means for at times supplying coded energy to the rails of said section adjacent the entrance end of the section, a first code responsive device having a winding at times connected across the rails of said section adjacent the entrance end of the section, a second code responsive device having a winding at times connected across the rails of said section adjacent the exit end of the section, a relay responsive to traffic conditions in the adjacent section in advance of said section and effective when said adjacent section in advance is vacant to condition the first supply means to supply energy to the rails of said section, to establish the circuit to connect the winding of the first code responsive device across the rails of said section, to render the second supply means ineffective to supply energy to the rails of said section, and to interrupt the circuit for connecting the second code responsive device across the rails of said section, said relay responsive to traffic conditions in said adjacent section in advance of said section being effective when said adjacent section in advance is occupied to interrupt the circuit for connecting the winding of the first code responsive device across the rails of said section, to establish the circuit connecting the winding of the second code responsive device across the rails of said section, to render the first supply means ineffective to supply energy to the rails of said section, and to condition the second supply means to supply energy to the rails of said section, and indication means controlled jointly by said first and second code responsive devices.

3. In combination, a section of railway track, a first supply means for at times supplying coded energy to the rails of said section adjacent the exit end of the section, a second supply means for at times supplying coded energy to the rails of said section adjacent the entrance end of the section, a first code responsive device having a winding to which energy is supplied from the rails of said section adjacent the entrance end of the section, a second code responsive device having a winding to which energy is supplied from the rails of said section adjacent the exit end of the section, a relay responsive to traffic

conditions in the adjacent section in advance of said section and effective when said adjacent section in advance is vacant to condition the first supply means to supply energy to the rails of said section, to render the second supply means ineffective to supply energy to the rails of said section, to render the first code responsive device responsive to coded energy supplied to the rails of said section, and to render the second code responsive device non-responsive to coded energy supplied to the rails of said section, said relay responsive to traffic conditions in said adjacent section in advance of said section being effective when said adjacent section in advance is occupied to condition the second supply means to supply energy to the rails of said section, to render the first supply means ineffective to supply energy to the rails of said section, to render the first code responsive device non-responsive to coded energy supplied to the rails of said section and to render the second code responsive device responsive to coded energy supplied to the rails of said section, an auxiliary relay, means responsive to code following operation of the first code responsive device for supplying energy to the winding of said auxiliary relay, means responsive to code following operation of the second code responsive device for also supplying energy to the winding of said auxiliary relay, and indication means controlled by said auxiliary relay.

4. In combination, a section of railroad track, a first track circuit for said track section comprising a first supply means for supplying coded energy to the rails of said section adjacent the exit end of the section and a first code responsive device having a winding to which energy may be supplied from the rails of said section adjacent the entrance end of the section, a second track circuit for said track section comprising a second supply means for supplying coded energy to the rails of said section adjacent the entrance end of the section and a second code responsive device having a winding to which energy may be supplied from the rails of said section adjacent the exit end of the section, a relay responsive to traffic conditions in the adjacent section in advance of said section and effective when said adjacent section in advance is vacant to render only the first track circuit operative and effective when said adjacent section in advance is occupied to render only the second track circuit operative, and indication means controlled jointly by said first and second code responsive devices.

5. In combination, a section of railroad track, a first track circuit for said section comprising means for supplying energy to the rails of the section adjacent the exit end of the section and an electroresponsive device having a winding to which energy is supplied from the rails of the section adjacent the entrance end of the section, a second track circuit for said section comprising means for supplying energy to the rails of said section adjacent the entrance end of the section and an electroresponsive device having a winding to which energy is supplied from the rails of the section adjacent the exit end of the section, a relay responsive to traffic conditions in the adjacent section in advance of said section and effective when said adjacent section in advance is vacant to render only the first track circuit operative and effective when said adjacent section in advance is occupied to render only the second track circuit operative, a pair of line wires

substantially coextensive with said track section, an auxiliary relay located adjacent the exit end of the section, means governed by the electroresponsive device of the first track circuit for supplying energy to the winding of said auxiliary relay over said line wires, and indication means controlled jointly by said auxiliary relay and by the electroresponsive device of the second track circuit.

6. In combination, a stretch of railroad track having adjoining forward and rearward track sections, a first track circuit for the rearward section comprising a first supply means for supplying energy to the section rails adjacent the exit end of the section and a first electroresponsive device having a winding to which energy is supplied from the track rails adjacent the entrance end of the section, a second track circuit for the rearward section comprising a second supply means for supplying energy to the section rails adjacent the entrance end of the section and a second electroresponsive device having a winding to which energy is supplied from the track rails adjacent the exit end of the section, a first auxiliary relay located adjacent the exit end of the rearward section, a second auxiliary relay located adjacent the entrance end of the rearward section and operative when and only when energized to condition the second supply means to supply energy to the rails of said rearward section, a pair of line wires substantially coextensive with said rearward section, means governed by traffic conditions in the forward section for supplying energy over said line wires to the second auxiliary relay, said means being effective to supply energy to said second auxiliary relay when said forward section is occupied, means governed by the first electroresponsive device for supplying energy over said line wires to the first auxiliary relay, and indication means controlled jointly by the first auxiliary relay and the second electroresponsive device.

7. In combination, a stretch of railroad track having adjoining forward and rearward track sections, a first track circuit for the rearward section comprising a first supply means for supplying energy to the section rails adjacent the exit end of the section and a first electroresponsive device having a winding to which energy is supplied from the track rails adjacent the entrance end of the section, a second track circuit for the rearward section comprising a second supply means for supplying energy to the section rails adjacent the entrance end of the section and a second electroresponsive device having a winding to which energy is supplied from the track rails adjacent the exit end of the section, a first auxiliary relay located adjacent the exit end of the rearward section, a second auxiliary relay located adjacent the entrance end of the rearward section and operative when and only when energized to condition the second supply means to supply energy to the rails of said rearward section, said second auxiliary relay being operative when energized to prevent energy to be supplied from the rearward section rails to the winding of the first electroresponsive device, a pair of line wires substantially coextensive with said rearward section, means operative when and only when the first electroresponsive device is supplied with energy to establish connection to supply energy over the line wires to the winding of the first auxiliary relay, said means being operative when and only when the first electroresponsive device is not supplied with energy to establish a circuit

through which energy may be supplied over the line wires to the winding of the second auxiliary relay, means governed by traffic conditions in the forward section for supplying energy over the line wires to the winding of the second auxiliary relay, said means being effective to supply energy to said second auxiliary relay when said forward section is occupied, and indication means controlled jointly by the first auxiliary relay and the second electroresponsive device.

8. In combination, a stretch of railroad track having adjoining forward and rearward sections, a first and a second track circuit for the rearward section, each of said track circuits comprising a supply device for supplying energy to the section rails at one end of the section and an electroresponsive device having a winding receiving energy from the section rails at the other end of the section, the supply device of the first track circuit being located at the exit end of the section and the supply device of the second track circuit being located at the entrance end of the section, means responsive to traffic conditions in said forward section, said means being effective when the forward section is vacant to establish connection between the devices of the first track circuit and the rails of the rearward track section, said means being effective when the forward section is occupied to establish connection between the devices of the second track circuit and the rails of said rearward section, an auxiliary relay located adjacent the exit end of the rearward section, means governed by the supply of energy to the electroresponsive device of the first track circuit for supplying energy to the winding of said auxiliary relay, and indication means controlled jointly by said auxiliary relay and the electroresponsive device of said second track circuit.

9. In combination, a stretch of railway track having adjoining forward and rearward track sections, a first and a second track circuit for said rearward section, each of said track circuits comprising a supply device for supplying energy to the section rails at one end of the section and an electroresponsive device having a winding to which energy may be supplied from the section rails at the other end of the section, the supply device of the first track circuit being located at the exit end of the section and the supply device of the second track circuit being located at the entrance end of the section, a line circuit substantially coextensive with said rearward section, a first auxiliary relay located at the exit end of the rearward section and a second auxiliary relay at the entrance end of the rearward section, means responsive to and operative on the supply of energy to the electroresponsive device of the first track circuit to supply energy over the line circuit to the winding of the first auxiliary relay, means governed by traffic conditions in the forward section for supplying energy over the line circuit to the winding of the second auxiliary relay, said means being effective to supply energy to said second auxiliary relay only when said forward section is occupied, said second auxiliary relay controlling the supply device of the second track circuit of said rearward section in such manner that said device is effective to supply energy to the section rails when and only when the second auxiliary relay is energized, and indication means controlled jointly by said first auxiliary relay and the electroresponsive device of the second track circuit of said rearward section.

10. In combination, a stretch of railway track having adjoining forward and rearward track sections, a first and a second track circuit for said rearward section, each of said track circuits comprising a supply device for supplying energy to the section rails at one end of the section and an electroresponsive device having a winding to which energy may be supplied from the section rails at the other end of the section, the supply device of the first track circuit being located at the exit end of the section and the supply device of the second track circuit being located at the entrance end of the section, a first auxiliary relay located at the exit end of the rearward section and a second auxiliary relay located at the entrance end of the rearward section, means operative on the supply of energy to the electroresponsive device of the first track circuit for said rearward section to supply energy to the winding of the first auxiliary relay, means governed by traffic conditions in the forward section for supplying energy to the winding of the second auxiliary relay, said means being effective to supply energy to said second auxiliary relay only when said forward section is occupied, said second auxiliary relay controlling the supply device of the second track circuit of said rearward section in such manner that said device is effective to supply energy to the section rails when and only when said second auxiliary relay is energized, and indication means controlled jointly by said first auxiliary relay and by the electroresponsive device of the second track circuit of said rearward section.

11. In combination, a stretch of railway track having adjoining forward and rearward track sections, a first and a second track circuit for said rearward section, each of said track circuits comprising a supply device for supplying energy to the section rails at one end of the section and an electroresponsive device having a winding to which energy may be supplied from the section rails at the other end of the section, the supply device of the first track circuit being located at the exit end of the section and the supply device of the second track circuit being located at the entrance end of the section, a first and a second auxiliary relay, means responsive to and operative on the supply of energy to the electroresponsive device of the first track circuit for supplying energy to the first auxiliary relay, means governed by traffic conditions in the forward section for supplying energy to the winding of the second auxiliary relay, said means being effective to supply energy to said second auxiliary relay only when said forward section is occupied, said second auxiliary relay controlling the supply device of the second track circuit and being operative when and only when energized to condition said device to supply energy to the rails of said rearward section, and indication means controlled jointly by said first auxiliary relay and the electroresponsive device of the second track circuit of said rearward section.

12. In combination, a stretch of railway track having adjoining forward and rearward track sections, a first and a second track circuit for said rearward section, each of said track circuits comprising a supply device for supplying energy to the section rails at one end of the section and an electroresponsive device having a winding to which energy may be supplied from the section rails at the other end of the section, the supply device of the first track circuit being located at the exit end of the section and the supply device

of the second track circuit being located at the entrance end of the section, means responsive to occupancy of said forward section for controlling the track circuits of the rearward section, said means being effective when said forward section is vacant to render the first track circuit operative and to render the second track circuit inoperative, said means being also effective when the forward section is occupied to render the first track circuit inoperative and the second track circuit operative, an auxiliary relay, means controlled by the electroresponsive device of the first track circuit for supplying energy to said auxiliary relay, and indication means controlled jointly by said auxiliary relay and the electroresponsive device of the second track circuit for said rearward section.

13. In combination, a stretch of railway track having adjoining forward and rearward track sections, a first and a second track circuit for said rearward section, each of said track circuits comprising a supply device for supplying energy to the section rails at one end of the section and an electroresponsive device having a winding to

5 which energy may be supplied from the section rails at the other end of the section, the supply device of the first track circuit being located at the exit end of the section and the supply device of the second track circuit being located at the entrance end of the section, means responsive to occupancy of said forward section for controlling the track circuits of the rearward section, said means being effective when said forward section is vacant to render the first track circuit operative and to render the second track circuit inoperative, said means being also effective when the forward section is occupied to render the first track circuit inoperative and the second track circuit operative, an auxiliary relay, means controlled by the electroresponsive device of the first track circuit for supplying energy to said auxiliary relay, means controlled by the electroresponsive device of the second track circuit for also supplying energy to said auxiliary relay, and indication means controlled by said auxiliary relay.

20 FRANK H. NICHOLSON.
